UNITED STATES PATENT OFFICE

110,191

DESIGN FOR A SHOE RETAINER

Elizabeth J. O'Brien, Boston, Mass.

Application July 17, 1936, Serial No. 63,908

Term of patent 3½ years

To all whom it may concern:

Be it known that I, Elizabeth J. O'Brien, a citizen of the United States, residing at Boston, in the county of Suffolk and State of Massachusetts, have invented a new, original, and ornamental Design for a Shoe Retainer, of which the following is a specification, reference being had to the accompanying drawing, forming part thereof.

The article is made of pile fabric and comprises wings and a body portion. The front ends of the wings are straight and the rear ends thereof and the sides of the body portion are scalloped. The article is to imitate a bird or aeroplane in flight.

I claim:

The ornamental design for a shoe retainer, as shown and described.

ELIZABETH J. O'BRIEN.
